(57) CLAIM

The ornamental design for a plantar fasciitis night splint, as shown and described.

DESCRIPTION

FIG. 1 is a front elevation view of a plantar fasciitis night splint showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is a perspective view thereof; and,

FIG. 9 is a perspective view of the plantar fasciitis night splint in a state of use.

The broken lines depict environmental structure associated with the plantar fasciitis night splint in a condition of use. The broken lines and subject matter they depict form no part of the claimed design.
